(57) **CLAIM**

I claim the ornamental design for a spray dispenser, as shown and described.

DESCRIPTION

FIG. 1 is a front perspective view of the spray dispenser; FIG. 2 is a front elevational view of the spray dispenser; FIG. 3 is a top plan view of the spray dispenser; FIG. 4 is a side elevational view of the spray dispenser; and, FIG. 5 is a rear elevational view of the spray dispenser. The broken lines in the drawings are for illustrative purposes only and form no part of the claimed design.
